BOTTLE CLOSURE

Frank J. Davis, Chicago, Ill., assignor, by mesne assignments, of two-thirds to Alfred J. Moldenhauer and one-third to Oscar M. Meusel, both of Chicago, Ill.

Application June 24, 1936, Serial No. 87,029

7 Claims. (Cl. 215—21)

This invention relates to bottle closures or stoppers and particularly to a stopper for attachment to a bottle to render the bottle non-refillable.

One object of the present invention is to provide a stopper which may be assembled outside the bottle and inserted complete in the neck of a bottle after the bottle has been filled.

Another object of the invention is to provide a stopper having novel means associated therewith for securing portions of the stopper together, and wherein the said means are adapted to cooperate with the neck portion of a bottle to prevent relative displacement of said means and portions of the stopper structure.

Another object of the invention is to provide a stopper having a ball valve, and wherein novel means are employed for directing the ball toward a valve seat when the bottle and neck portion 20 thereof are in substantially horizontal position.

A further object of the invention is to provide a bottle stopper adapted for attachment to a particular type of bottle neck construction.

A still further object of the invention is to improve devices of the character described in sundry details hereinafter referred to and particularly pointed out in the appended claims.

One embodiment of the present invention is shown for illustrative purposes in the accompanying drawing, in which:

Fig. 1 is a sectional elevational view of a bottle neck illustrating the application of my improved stopper thereto;

Fig. 2 is a sectional elevational view similar to Fig. 1, and taken substantially as indicated by the line 2—2 thereof;

Fig. 3 is a plan sectional view taken substantially as indicated by the line 3—3 of Fig. 1; and

Fig. 4 is an exploded view illustrating in perspective certain cooperating elements employed in the construction of my improved stopper.

In the drawing, the illustrative embodiment of the present invention is shown applied to a particular form of bottle neck 5 having an internal 45 annular groove or recess 6 formed therein, the illustrative embodiment of the improved stopper, in the present instance, comprising a body member 7 formed, preferably, of glass and having an aperture 8 formed therein communicating with the interior of the bottle, and having a valve seat 9 formed adjacent and surrounding one end of the aperture 8, the valve seat 9 being adapted to receive a valve member shown, in the present instance, as a ball 11 when the bottle is in up- 50 right position.

For securing the body member 7 rigidly within the neck of the bottle, the outer sides of the lower portion of the body member 7 are provided with a plurality of annular ribs 12 adapted to be engaged by a sleeve 13 formed, preferably, of compressible resilient material such, for example, as cork, rubber or the like, adapted to fit snugly within the neck of the bottle and, as in the illustrative embodiment, to extend into the annular groove 6 of the bottle neck 5 in order to secure 10 the body member 7 more rigidly therein.

Formed adjacent the upper portion of the body member 7 are a plurality of annularly spaced fingers 14 surrounding the ball 11 in a manner to maintain the ball in substantial alignment 15 with the aperture 8 in a manner to efficiently cooperate with the valve seat formed on the member 7, the slots or open portions 15 between the fingers 14 being provided for the free discharge 20 of fluid from the bottle when tilted and the ball 20 removed from its seat.

Mounted on the body member 7 and indicated, as a whole, by the numeral 16, is a cap member formed, preferably, of glass or the like and having a bail-like retaining portion 17 adjacent its upper end for retaining the ball valve 11 against displacement from within the surrounding fingers 14, the portion 17 being, preferably, spaced from the bottle neck 5 and cut away as indicated at 18 to permit discharge of fluid from the bottle, 30 the cap member 16 also having oppositely disposed apertures 19 formed therein for discharge of fluid outwardly to the mouth portion 20 of the bottle neck, which, in the present instance, is shown as having an ordinary closure member or 35 cork 21 placed therein after the bottle has been filled and my improved stopper has been inserted in proper position, the cork 21 being found desirable in the shipping or transporting of the bottles after being filled.

It will be noted particularly by reference to Figs. 1 and 2, that the inner faces 22 of the fingers 14 are inclined at an angle to the axial center line of the body member 7 and bottle neck 5 in a manner to direct the ball valve 11 toward the 45 seat 9 when the stopper and bottle are in substantially horizontal position, thereby preventing the filling of the bottle when in a position to receive a fluid or the like, and to prevent the retention of fluid above the stopper in restoring the bottle 50 to its normal upright position.

For securing the body member 7 and cap member 16 together, the body member 7 is provided with an outwardly extending annular projection 23 adapted to be engaged by inwardly extending 55

end portions 24 (Fig. 2) of an inverted substantially U-shaped clip indicated as a whole by the numeral 25 positioned in recesses 26 and 27 formed in the upper and outer surfaces, respectively, of the cap member 16 as clearly illustrated in Figs. 1, 2, 3 and the upper portion of Fig. 4, the side or leg portions 28 of the clip 25, when my improved stopper is in place in the bottle, being positioned closely adjacent the inner side or surface of the bottle neck 5 as clearly shown in Fig. 2 to prevent disengagement of the inwardly extending end portions 24 of the clip from the projection 23 formed on the body member 7, thereby providing a structure wherein any tampering or attempt to remove the improved stopper will result only in failure or in breakage of the elements to such an extent as to render the stopper inadequate for further use.

It will be observed from the foregoing description that the present invention provides a bottle stopper of novel construction and arrangements, which may be assembled outside the bottle and inserted complete in the neck portion thereof after the bottle has been filled, and in a manner 25 to prevent refilling of the bottle after the contents have been dispensed therefrom, and wherein novel means for securing portions of the stopper together are adapted to cooperate with the neck portion of the bottle to prevent relative displacement of said means and portions of the stopper structure; also that the present invention provides novel means for directing the ball valve toward the valve seat when the bottle and neck portion thereof are in substantially horizontal 35 position, and wherein my improved stopper is adapted for attachment to a particular type of bottle neck construction.

Obviously, the present invention is not limited to the precise construction and arrangement shown and described, as the same may be variously modified. Moreover, all the features of the invention need not be used conjointly, as the same may be used to advantage in variously different combinations and subcombinations.

45 What I claim as new and desire to secure by Letters Patent is:

1. In a stopper for attachment to a bottle to render the same non-refillable, the combination of a body member rigidly secured in the neck of a bottle, said member having an aperture formed therein communicating with the interior of the bottle and having a valve seat surrounding said aperture, an outwardly extending projection on said body member, a valve member engageable with said seat, a plurality of fingers on said body member and annularly spaced around said valve member, an apertured cap member engaging said body member, a clip engaging said cap member and the projection on said body member for securing the cap member and body member together, and retaining means on said cap member for retaining said valve member against displacement with respect to said fingers.

2. In a stopper for attachment to a bottle to render the same non-refillable, the combination of a body member rigidly secured in the neck of a bottle, said member having an aperture formed therein communicating with the interior of the bottle and having a valve seat surrounding said aperture, an outwardly extending projection on said body member, a valve member engageable with said seat, a plurality of fingers on said body member and annularly spaced around said valve member, means on said fingers for directing said valve member toward said seat when the bottle is

in a horizontal position, an apertured cap member engaging said body member, and a clip engaging said cap member and the projection on said body member for securing the cap member and body member together.

3. In a stopper for attachment to a bottle to render the same non-refillable, the combination of a body member rigidly secured in the neck of a bottle, said member having an aperture formed therein communicating with the interior of the bottle and having a valve seat surrounding said aperture, an outwardly extending projection on said body member, a valve member engageable with said seat, a plurality of fingers on said body member and annularly spaced around said valve member, the inner surface of said fingers inclined to a line extending axially of said body member and bottle for directing said valve member toward said seat when the bottle is in horizontal position, an apertured cap member engaging said body member and the projection thereon, and a clip engaging said cap member and the projection on said body member for securing the cap member and body member together.

4. In a stopper for attachment to a bottle to render the same non-refillable, the combination of a body member having a resilient sleeve mounted thereon and rigidly secured in the neck of a bottle, said member having an aperture formed therein communicating with the interior of the bottle and having a valve seat surrounding said aperture, an outwardly extending annular projection on said body member above said sleeve, a ball valve member engageable with said seat, a plurality of fingers on said body member and annularly spaced around said valve member, an apertured cap member having a recess formed therein and engaging said body member, a clip in the recess of said cap member and having inwardly extending end portions engaging the projection on said body member for securing the cap member and body member together, and retaining means on said cap member for retaining said valve member against displacement with respect to said fingers.

5. In a stopper for attachment to a bottle to render the same non-refillable, the combination of a body member having a plurality of annular ribs formed thereon, a sleeve of resilient compressible material surrounding said member and engaging said ribs, said body member and sleeve being rigidly secured in the neck of a bottle, said member having an aperture formed therein communicating with the interior of the bottle and having a valve seat surrounding said aperture, an outwardly extending annular projection on said body member above said sleeve, a ball engageable with said seat, a plurality of guide fingers on said body member and annularly spaced around said ball, the inner surfaces of the respective fingers being inclined to a line extending axially of said body member and bottle for directing said ball toward said seat when the bottle is in a horizontal position, an apertured cap member engaging said body member and outwardly extending projection thereon, said cap member having communicating recesses formed in the surface thereof, a clip positioned in said recesses and having inwardly extending end portions engaging the projection on said body member for securing the cap member and body member together, and retaining means on said cap member for retaining said ball against displacement with respect to said fingers.

6. In a stopper for attachment to a bottle to render the same non-refillable, the combination with a bottle neck having an internal annular groove, of a body member having a plurality of 5 annular ribs formed thereon, a sleeve of resilient compressible material surrounding said member and engaging said ribs and groove, said body member and sleeve being rigidly secured in the neck of the bottle adjacent said groove, said 10 member having an aperture formed therein communicating with the interior of the bottle and having a valve seat surrounding said aperture, an outwardly extending projection on said body member, a ball engageable with said seat, a plurality of guide fingers on said body member and 15 annularly spaced around said ball, a cap member engaging said body member and outwardly extending projection thereon, said cap member having apertures formed therein communicating 20 with the interior of said body member and having communicating recesses formed in the surface of said cap, a clip positioned in said recesses and having inwardly extending end portions engaging the projection on said body member for securing 25 the cap member and body member together, said clip being positioned closely adjacent the inner side of said bottle neck to prevent disengaging of the inwardly extending end portion of the clip from the projection on said body member, 30 and retaining means on said cap member for retaining said ball against displacement with respect to said fingers.

7. In a stopper for attachment to a bottle to render the same non-refillable, the combination 35 with a bottle neck having an internal annular groove formed therein, of a body member having

a plurality of annular ribs formed thereon, a sleeve of resilient compressible material surrounding said member and engaging said ribs and groove, said body member and sleeve being rigidly secured in the neck of the bottle adjacent 5 said groove, said member having an aperture formed therein communicating with the interior of the bottle and having a valve seat surrounding said aperture, an outwardly extending annular projection on said body member above said sleeve, 10 a ball engageable with said seat, a plurality of guide fingers on said body member and annularly spaced around said ball, the inner surfaces of the respective fingers being inclined to a line extending axially of said body member and bottle 15 for directing said ball toward said seat when the bottle is in a horizontal position, a cap member engaging said body member and outwardly extending projection thereon, said cap member having oppositely disposed apertures formed therein 20 communicating with the interior of said body member and having communicating recesses formed in the top and side surfaces of said cap, a U-shaped clip positioned in said recesses and having inwardly extending end portions engaging 25 the projection on said body member for securing the cap member and body member together, said clip being positioned closely adjacent the inner side of said bottle neck to prevent disengaging of the inwardly extending end portions 30 of the clip from the projection on said body member, and retaining means on said cap member for retaining said ball against displacement with respect to said fingers.
